(57) **CLAIM**

The ornamental design for a liquid applicator, as shown and described.

DESCRIPTION

FIG. 1 is a top perspective view of a liquid applicator showing our new and ornamental design;

FIG. 2 is a bottom perspective view thereof;

FIG. 3 is a left side view thereof;

FIG. 4 is a right side view thereof;

FIG. 5 is a bottom plan view thereof;

FIG. 6 is a top plan view thereof;

FIG. 7 is a front view thereof; and,

FIG. 8 is a rear view thereof.

The dot-dash broken lines depict portions of the liquid applicator that form no part of the claimed design. The bottom view is included, even though it only shows disclaimed matter, for the purpose of showing environment.
